UNITED STATES PATENT OFFICE.

GEORGE H. PERRINE, OF GREENBURG, NEW YORK, ASSIGNOR TO SCOVILL MANUFACTURING COMPANY, OF WATERBURY, CONNECTICUT, A CORPORATION OF CONNECTICUT.

SPRING-CONNECTOR FOR SUSPENDERS AND THE LIKE.

1,171,873.

Specification of Letters Patent. Patented Feb. 15, 1916.

Application filed July 29, 1915. Serial No. 42,485.

To all whom it may concern:

Be it known that I, GEORGE H. PERRINE, a citizen of the United States, residing at Greenburg, in the county of Westchester and State of New York, have invented a certain new and useful Improvement in Spring-Connectors for Suspenders and the like, of which the following is a full, clear, and exact description.

10 This invention relates to elastic connections for connecting the opposing ends of straps or webbing, such as are used in suspenders and the like garment supporters or other articles.

15 The object of the invention is to provide an elastic or spring connector or connection for suspenders and the like of simple and economical construction, whereby easy and comfortable movements of the body of the 20 wearer may be permitted without annoying strains and pulls upon the body of the wearer by the straps or webbing of the suspenders or other article.

The invention consists in an elastic or 25 spring connector for suspenders and the like, constructed of a single piece of wire preferably bent in the form of a ring or circle, and having its ends returned and carried substantially centrally across the ring and terminating in eyes loosely engaging the wire upon the opposite side of the ring, said returned ends being adapted to be engaged by the opposing ends of the straps or webbing of the suspenders or other article, all substantially as I will proceed now more particularly to set forth and finally claim.

In the accompanying drawings illustrating the invention in the several figures of which like parts are similarly designated, 40 Figure 1 is a rear view of a portion of a man's body, showing a pair of overalls the suspenders of which are provided with the invention. Fig. 2 is an elevation of the elastic or spring connecting device. Fig. 3 is 45 an edge view of the device looking from left to right of Fig. 2. Fig. 4 is an edge view of the device looking from right to left of Fig. 2. Fig. 5 is an edge view of the device looking from above Fig. 2. Fig. 6 is an elevation showing one of the positions which the two spring members of the device assume when subjected to strain.

In Fig. 1 the invention is shown as applied to the back of the suspenders of a pair 55 of overalls, and in said figure, 1 are the

shoulder straps and 2 the suspender ends or button engaging portions, and 3 the elastic or spring connecting device. The elastic or spring connecting device is constructed of a single piece of spring wire, bent to form 60 a ring or annular frame 4, with the wire at the meeting point slightly overlapping and left free or disconnected as at 5, and then bent inwardly and returned substantially diametrically across the ring to form two 65 substantially horizontal and spaced bars 6 and 7, the ends of said bars being bent and returned at right angles to the plane of the ring upon themselves to form elongated eyes 8 and 9 embracing the wire upon the 70 opposite side of the ring with a slip fit.

In Fig. 6 I have shown the relative positions of the parts of the device which they will assume when the device is subjected to strains or pulls upon the opposing parts of 75 the suspenders or other article to which the device is applied and when in use, these bars maintaining a substantially parallel relation while in use or under strain in a substantially direct line. As thus constructed, the device comprises substantially 80 two resilient or spring members having their point of connection at a point in the ring or frame substantially diametrically opposite the open or overlapping part of the ring and 85 it will be seen that each portion is a spring in itself, and that the device as a whole has resiliency in all directions. The device is applied to the suspenders or other article by 90 passing the opposing straps or webs of such article between and around the bars 6 and 7, as shown in Fig. 1. The shoulder straps 1 are passed through the device and around the bar 6 so as to have a sliding engagement therewith, and the suspender ends or button 95 engaging portion are passed through the device upon the opposite side and around the bar 7 so as to have a sliding engagement, and when in use it will be seen that the resiliency of the parts in all directions will permit 100 perfect freedom of movement of the body of the wearer in all directions and without annoying strains or pulls upon the body and without inconvenience or uncomfor- 105 tability to the wearer.

The position of the parts of the device shown in Fig. 6 is merely that which is effected by pull or strain in direct longitudinal or vertical direction, whereas in the 110 actual use of the device the inherent resili-

ency of the parts of the device will yield to strains in all directions.

It is to be noted that the resiliency of the device is rendered most effective by the crossing of the bars 6 and 7 at point 5, because the pull of the suspenders is transmitted through the bars to opposite arcs of the ring. It is deemed essential also that these bars should have the terminal eyes 8 and 9 engaged with the ring on the arc opposite their point of crossing 5, since thereby the recoil is arrested by contact of the eyes, the strain is borne mainly by the arcs opposite the bars, and the suspender loops cannot slip off of the bars or get out of position thereon.

Although the main part of the device is here shown as formed in circular shape, it will be understood that this portion of the device may be constructed of any other shape or design which will serve the purpose and intent of the invention, and I wish it to be understood that the invention is not limited to the particular circular shape of the main part of the device.

What I claim is:—

1. A spring connector for suspenders and the like, constructed of wire in ring form and open at one point in its circumference and the ends at this point crossed and extended from the open part across the ring and slidably engaging the opposite arc of the ring.
2. A spring connector for suspenders and

the like, constructed of a single piece of wire bent in ring form and left open at one point in its circumference and the ends at this point crossed and extended across the ring and terminating in eyes slidably engaging the opposite side of the ring.

3. A spring connector for suspenders and the like consisting of a spring wire bent into annular shape and having its ends crossed at their meeting point and extending thence as bars crosswise of the device to an opposite point, said bars movably connected with the device at such opposite point and serving to receive the suspender parts to be connected.

4. A spring connector for suspenders and the like formed of a single spring wire bent into an annular form and having its ends bent at their meeting point and overlapped thereat and forming bars extending across the device to an opposite point and slidably connected with the device at said opposite point and adapted to receive the opposing straps of the suspenders so that pulls on said straps will tend to separate said bars and compressibly distort the annular form of said device to thereby cause its spring action to become effective.

In testimony whereof I have hereunto set my hand this 27th day of July A. D. 1915.

GEORGE H. PERRINE.
